SPEED CONTROLLED CONTACT ARRANGEMENT

Albin Buchmann, Soleure, Switzerland, assignor to Scintilla Ltd., Soleure, Switzerland

Application June 4, 1952, Serial No. 291,751

Claims priority, application Switzerland June 5, 1951

16 Claims. (Cl. 200—80)

1 The present invention relates to a speed controlled contact arrangement for making and breaking the contact between a pair of electrical contacts when a predetermined speed of a rotary member is obtained.

More particularly, the present invention relates to a device which may be used to adjust the rotating speed of electrical motors, adapted to operate at different speeds, by periodically interrupting the circuit to such electric motors when the desired rotating speed is obtained.

One of the objects of the present invention is to provide a device of the above type which consists of very few parts, and which is easily constructed.

A further object of the present invention is to provide a device of the above type which is of great sensitivity.

A still further object of the present invention is to provide a device of the above type which is capable of operating with a high degree of efficiency at substantially all speed ranges of a given motor.

Yet another object of the present invention is to provide a means for adjusting a device of the above type so that a motor may be controlled to operate at a desired, given speed.

With the above objects in view, the present invention mainly consists of a speed controlled electrical contact arrangement comprising a support means having a first contact member mounted thereon for movement, in a predetermined direction, from an initial position and permanently tending to return to this initial position. A second contact member is movably mounted on this support together with a means for adjusting the position of this second contact member so that it contacts the first contact member when the latter is located either in its initial position or between this initial position and another position, the degree of displacement of the first contact member from its initial position while making contact with the second contact member depending upon the adjustment of the latter. A rotatable member rotating at variable speeds is located adjacent the first contact member and actuates a means for moving the first contact member periodically from its actual position in a direction away from its initial position to a position spaced from this initial position by a distance varying and proportional to the speed of the rotatable member so that this distance increases with an increase in the rotative speed of the rotatable member.

The novel features which are considered as

2 characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a sectional view of an apparatus constructed in accordance with the present invention and taken along line A—A of Fig. 3 in the direction of the arrows;

Fig. 2 is a view of the structure of Fig. 1 in a different position thereof;

Fig. 3 is a plan view of the apparatus of Fig. 1;

Fig. 4 is a side, sectional view of a different embodiment of the structure shown in Fig. 1; and

Fig. 5 is a fragmentary, sectional view of yet another embodiment of the invention.

Referring now to the drawings, there is shown in Figs. 1, 2 and 3, a support having an insulating block 5 mounted thereon. This insulating block has fixedly connected thereto, by means of rivets 8 and 9, the springy, electrically conductive, members 6 and 7, respectively. As is apparent from the drawings these springy members 6 and 7 are each connected at one end to an underside of the block 5, extend over the latter in substantially perpendicular directions, respectively, with the member 7 located over the member 6. Fixed to member 7 is a contact 11, and fixed to member 6 is a contact 10 located directly beneath contact 11. As is shown in Fig. 2, the contacts 10 and 11 are connected, through members 6 and 7, into the electrical circuit of a motor whose speed is to be regulated and which is diagrammatically illustrated in Fig. 2.

The shaft 1 may be interconnected with the motor to be regulated in any suitable way so as to rotate at a speed equal or proportional to the speed of the motor. For example, the shaft 1 may be part of the motor shaft. As is clearly illustrated in the drawings, the shaft 1 extends through the block 5 and has an end thereof turnably mounted in the bearing 2. A weight disc 3 is pivotally mounted by means of pin 4 for turning movement about an axis normal to the axis of shaft 1, and this weight disc 3 is formed with a pair of recesses 3' respectively located on opposite sides of shaft 1 and in opposite faces of disc 3 so that the latter is unbalanced and upon rotation of shaft 1 tends to turn about the axis of pin 4 from the position shown in Fig. 2 to that shown in Fig. 1.

In a bore formed in a support 14 there is turn-

ably mounted a shaft 15 having a knurled, manually engageable end 17 and carrying on its opposite end a cam 16 located against the top side of member 6 so that by turning of shaft 15 the cam 16 will adjust the position of stationary contact 11. An insulating disc 13 is mounted on the member 6 about the opening 12 thereof, through which the shaft 1 extends, so as to be located between member 6 and disc 3.

The operation of the above-described structure 10 is as follows:

In the position of rest, the parts assume the position shown in Fig. 2 where the resiliency of member 6 keeps contact 10 in engagement with contact 11 and keeps insulating disc 13 against disc 3 to maintain the latter in an unbalanced position thereof. When the motor is started, the shaft 1 rotates and, by centrifugal action, the disc 3 will turn about the axis of pin 4 from the position shown in Fig. 2 toward that shown 20 in Fig. 1. When the speed of the shaft 1 has increased to a predetermined value, the disc 3 will have assumed a certain tilted position at which the lowermost point thereof will contact the member 13 along a circle located about the 25 axis of shaft 1.

As is apparent from Figs. 1 and 2, the member 6 forms a lever arm. Thus, when the lowermost point of disc 3 moves along the contact circle on member 13, the disc 3 will encounter different 30 counter forces from the lever arm formed by member 6, and these counter forces will be at a minimum when the lowermost point of disc 3 is most distant from contact 11, since at this time the lever arm is longest, and when this lowermost 35 point of disc 3 is located nearest to contact 11, the lever arm of member 6 is shortest and produces the greatest counter force against the disc 3.

As a result of this construction, the shaft 1 will increase its speed until the disc 3 assumes a tilted 40 position where the lowermost point thereof moves contact 10 away from contact 11 when this lowermost point is located most distant from contact 11, so as to break the circuit to the motor. However when this lowermost point of disc 3 is nearest to contact 11, it is unable to overcome the counter 45 force of the shortened lever arm and therefore the contact 10 moves back into engagement with contact 11, by the springy force of member 6, to again complete the circuit to the motor. Thus, the above described structure provides a means for making and breaking the engagement 50 of contacts 10 and 11 at 180° intervals of the turning of the shaft 1, and during the rotation of shaft 1, at the speed for which the apparatus is set, the arm 6 vibrates at a relatively high frequency to continually make and break the circuit to the motor so as to control the speed of the latter.

The parts 15-17 are adapted to set the contacts 10 and 11 to be separated at a predetermined speed of shaft 1. Thus, if shaft 15 is in the position shown in Fig. 2 and is turned to move contact 11 downwardly, as viewed in Fig. 2, it is apparent that the contact 10 and member 6 will be moved downwardly to locate the free right-hand end of member 6, as viewed in Fig. 2, at a further distance beneath the pin 4, when the apparatus is in its position of rest, than is the case with the position of the parts shown in Fig. 2. Therefore, in order to separate contacts 10 and 11, the disc 3 would have to turn through a greater angle about the axis of pin 4 than is the case with the setting illustrated in Fig. 2, and since a higher speed of rotation of shaft 1 is

required to increase the angle through which disc 3 turns about the axis of pin 4, the adjusted speed of the motor would be appreciably increased.

It is therefore apparent that the member 6, 5 and contact 10 therewith, are movable from an initial position, where the free end of member 6 is directly beneath the disc 3 and maintains the latter normal to the shaft 1, as shown in Fig. 2, when the parts are at rest, to another position, controlled by adjustment of contact 11, further away from the pin 4 than the initial position, the member 6 and contact 10 therewith being periodically movable by rotation of shaft 1, away from its actual, adjusted rest position located at the initial position or at a predetermined distance from the initial position.

With conventional speed regulators, it is usual that the motor speed will fluctuate in the lower speed ranges so that control at such lower speed ranges is practically non-existent. The disclosed structure is particularly suited for high sensitivity at such lower speed ranges by structures similar to those shown in Figs. 4 and 5. In Fig. 4, the motor shaft 18 and shaft 1 are interconnected by gearing 19, 20 which causes the shaft 1 to turn at twice the speed of shaft 18. Thus, even when the motor shaft 18 turns at a relatively low speed, the shaft 1 is still turning at a speed sufficient to cause an efficient operation of the speed controlled apparatus for making and breaking the engagement between contacts 10 and 11, this apparatus which is illustrated in Fig. 4 being exactly the same as that described above except for the connection of shaft 18 to shaft 1 by gears 19 and 20.

It may be desirable in some instances to adjust the ratio between the speeds of shafts 1 and 18, and for this purpose the structure of Fig. 5 is suitable. As is shown in Fig. 5, the shaft 2 carries 40 a friction wheel 24 of relatively small diameter adapted to be contacted and turned by the friction member 23 having a conical outer face 23' and being formed with an annular groove 23''. This member 23 is slidable along shaft 18 while being constrained by a key to rotate therewith, and the position of member 23 is regulated by 45 turning of lever 22 which is pivotally mounted on support 21 and has a free end located in groove 23''. Thus, as the member 23 is moved upwardly, as viewed in Fig. 5, the turning speed of shaft 1 will constantly increase with respect to the turning speed of shaft 18.

It is evident that some means must be provided to maintain friction wheel 24 in contact with member 23 during adjustments of the latter. This means may take any suitable form. For example, the support may be furnished with swivelling means 25 (see Fig. 5) in connection with a bracket 26, such swivelling means being 50 suitably positioned in such a way as to enable shaft 1 to be urged to approach the motor shaft 18 by the action of a spring 27, or to diverge from the same, according to whether the friction member 23 is lowered or raised, as the case may be.

In another example, wherein the support is stationary, directly beneath the bearing 2, shaft 1 may be provided with a universal joint interconnecting the lower portion of shaft 1, on which wheel 24 is located, with the remainder of the shaft 1.

In the former example, one end of the spring 27 is fixed to a post 29 on the bracket 26 and the other end is attached to a second post 30 on the support, whereas, in the latter example,

the second end of the spring is attached by any suitable means to the free end of the shaft 1.

It will be understood that each of the elements described above, or two or more together, may also find a useful application in other types of speed controlled contact arrangements, differing from the types described above.

While the invention has been illustrated and described as embodied in a speed controlled contact arrangement for setting the speed of a motor, or the like, at a desired value, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptions should and are intended to be comprehended within the meaning and range of equivalence of the following claims.

What is claimed as new and desired to be secured by Letters Patent is:

1. A speed controlled contact arrangement, comprising, in combination, support means; a first contact member mounted on said support means for movement, in a predetermined direction, from an initial position and permanently tending to return to said initial position; a second contact member movably mounted on said support means; means for adjusting the position of said second contact member to make contact with said first contact member when the latter is located in said initial position thereof and between said initial position and another position, the degree of displacement of said first contact member from said initial position while said contact members are in engagement with each other depending upon the adjustment of said second contact member; a rotatable member rotating at a variable speed; and means actuated by said rotatable member and moving said first contact member periodically from its actual position in a direction away from its initial position to a position spaced from said initial position by a distance varying and proportional to the speed of said rotatable member so that said distance increases with an increase in the rotative speed of said rotatable member.

2. A speed controlled contact arrangement, comprising, in combination, support means; a first contact member mounted on said support means for movement, in a predetermined direction, from an initial position and permanently tending to return to said initial position; a second contact member mounted on said support means and contacting said first contact member in one position of the latter; a rotatable member rotating at a varying speed; and means actuated by said rotatable member for moving said first contact member periodically from said one position, in a direction away from said initial position thereof, to another position spaced from said initial position by a distance proportional to the speed of said rotatable member so that said distance increases with an increase in speed of said rotatable member.

3. A speed controlled electrical contact arrangement, comprising, in combination, support means; a pair of contacts mounted on said sup-

port means and located in an electrical circuit for completing and breaking the same, at least one of said contacts being mounted on said support for movement toward and away from the other of said contacts; a shaft portion mounted, for turning movement about its own axis, on said support means; weight means pivotally mounted on said shaft portion for turning movement, through an angle proportional to the rotating speed of said shaft portion, about a second axis normal to said axis of said shaft portion upon rotation of the latter; and control means operatively connected to said one of said contacts and being located adjacent to said weight means to be engaged thereby for moving said one contact out of engagement with the other of said contacts when said weight means turns about said second axis, upon rotation of said shaft portion, through a predetermined angle proportional to the speed of rotation of said shaft portion.

4. A speed controlled electrical contact arrangement, comprising, in combination, support means; a pair of contacts mounted on said support means and located in an electrical circuit for completing and breaking the same, at least one of said contacts being mounted on said support for movement toward and away from the other of said contacts; a shaft portion mounted, for turning movement about its own axis, on said support means; weight means pivotally mounted on said shaft portion for turning movement through an angle proportional to the rotating speed of said shaft portion, about a second axis normal to said axis of said shaft portion upon rotation of the latter; spring means operatively connected to said one of said contacts for urging the same against the other of said contacts; and control means operatively connected to said one of said contacts and being located adjacent to said weight means to be engaged thereby for moving said one contact against the action of said spring means out of engagement with the other of said contacts when said weight means turns about said second axis, upon rotation of said shaft portion, through a predetermined angle proportional to the speed of rotation of said shaft portion.

5. An arrangement as defined in claim 4 and wherein an adjusting means is operatively connected to the other of said contacts to locate the same at a predetermined distance from a plane normal to said axis of said shaft portion and including said second axis so as to thereby adjust the extent of turning movement of said weight means about said second axis necessary to move said one contact away from said other contact.

6. A speed controlled electrical contact arrangement, comprising, in combination, support means; a shaft portion mounted, for rotation about its own axis, on said support means; an elongated springy contact member fixed to said support means, having a contact portion intermediate the length thereof, and having a free end portion formed with an opening through which said shaft portion extends; a stationary contact located on one side of said springy contact member and contacting said contact portion thereof; weight means mounted on said shaft portion, on the same side of said contact member as said stationary contact, for pivotal movement through an angle proportional to the speed of rotation of said shaft portion, about a second axis normal to said axis of said shaft portion upon rotation of the latter, said weight means being located adjacent to said contact member so as

to move the same, and said contact portion thereof, away from said stationary contact when said shaft portion turns at a speed sufficient to turn said weight means about said second axis through such an angle that said weight means engages said contact member.

7. An arrangement as defined in claim 6 and wherein said weight means is in the form of a disc formed with a central aperture through which said shaft portion extends, and being formed with a pair of recesses respectively located on opposite sides of said shaft portion and in opposite faces of said disc.

8. A speed controlled contact arrangement, comprising, in combination, support means; a shaft mounted, for rotation about its own axis, on said support means; elongated springy contact means having a contact portion intermediate the length thereof, being fixedly connected at one end thereof to said support means, and having an opposite free end portion formed with an opening through which said shaft extends; a stationary contact mounted on said support means, being located on one side of said contact means, and contacting said contact portion thereof to maintain said contact means, against its own resilient force, in a predetermined position; a weight disc formed with an aperture through which said shaft extends, being pivotally mounted on the latter for turning movement about a pivot axis normal to said shaft axis, being located on said one side of said contact means, and being formed with a pair of recesses respectively located on opposite sides of said shaft and in opposite faces of said weight disc, the latter being located adjacent to said contact means so that upon rotation of said shaft at a predetermined speed said weight disc engages said contact means about a circle having its center in said shaft axis so as to move said contact portion of said contact means from said stationary contact.

9. An arrangement as defined in claim 6 and wherein an adjusting means is operatively connected to said stationary contact for locating the same at a predetermined distance from a plane normal to said axis of said shaft portion and including said second axis.

10. An arrangement as defined in claim 9 and wherein said stationary contact is in the form of a springy contact member and wherein said adjusting means comprises a turnable cam located against said stationary contact for adjusting the location thereof.

11. An arrangement as defined in claim 6 and wherein a motor shaft is interconnected with said shaft portion by a transmission means for turning said shaft portion at a speed approximately twice that of the motor shaft.

12. An arrangement as defined in claim 6 and wherein a motor shaft is interconnected with said shaft portion by an adjustable transmission means for adjusting the turning speed of the motor shaft to a predetermined fraction of the turning speed of said shaft portion.

13. A speed controlled contact arrangement, comprising, in combination, support means; a first contact member mounted on said support means for movement in a predetermined direction from an initial position and permanently tending to return to said initial position; a second contact member mounted on said support means also for movement in said predetermined direction and being located in the path of said first contact member and abutting against the same; means for adjusting the position of said second contact member so as to move said first contact member, from said initial position thereof, an adjustable distance in said predetermined direction; a rotatable member rotating at a variable speed; and means actuated by said rotatable member and adapted to move said first contact member periodically in a direction away from its initial position to a position spaced from said initial position by a distance varying and proportional to the speed of said rotatable member so that said distance increases with an increase in the rotative speed of said rotatable member, whereby when said distance is greater than the actual distance of said first contact member from its initial position, obtained by adjustment of said second contact member, said first contact member will be periodically moved out of contact with said second contact member.

14. A speed controlled contact arrangement as defined in claim 13 and wherein said first contact member is in the form of an elongated springy element fixedly connected at one end thereof to said support means and having an opposite free end portion formed with an aperture through which said rotatable member extends.

15. A speed controlled contact arrangement as defined in claim 14 and wherein said means actuated by said rotatable member is in the form of a disc formed with an aperture through which said rotatable member extends, mounted on said rotatable member for free pivotal movement about an axis normal to the axis of rotation of said rotatable member, and being formed with a pair of recesses respectively located on opposite sides of said rotatable member and in opposite faces of said disc, the latter being located adjacent to said free end portion of said first contact member.

16. A speed controlled contact arrangement as defined in claim 15 and wherein said second contact member also is in the form of an elongated springy element fixedly connected at one end thereof to said support means, and wherein said means for adjusting the position of said second contact member is in the form of a turnable cam engaging said second contact member at an intermediate part thereof.
